UNITED STATES PATENT OFFICE.

JAMES N. STACY, OF PORTLAND, OREGON, ASSIGNOR OF ONE-HALF TO SARA W. COE,
OF NEW YORK, N. Y.

MEMORANDUM CASE AND REGISTER.

965,141.

Specification of Letters Patent. Patented July 19, 1910.

Application filed March 8, 1909. Serial No. 482,054.

To all whom it may concern:

Be it known that I, JAMES N. STACY, citizen of the United States, residing at Portland, in the county of Multnomah and State 5 of Oregon, have invented certain new and useful Improvements in Memorandum Case and Register, of which the following is a specification.

This invention relates to articles of stationery, and particularly to an apparatus 10 for holding a roll of writing paper and delivering the same as needed, and re-winding the roll when written upon.

The object of my invention is to provide a 15 device which, made in various sizes, may be used as a means for carrying a roll of paper which may be unreeled as desired, and used, this roll to be used for the purpose of writing lectures, sermons or other matter of like 20 character, which, after being written upon the roll of paper, may be rewound and then unrolled by the person delivering the lecture or sermon.

In its smaller forms, the device is also 25 useful as a means for conveniently holding notes made for lectures, sermons, etc., and in this form, is intended to be held in the hand and the roll to be gradually unwound as the notes are needed.

30 The invention may also be used as a record holder for the purpose of keeping accounts and like memoranda, and in this connection also it is provided with means whereby the paper upon which a message is 35 written, after having been rolled up on the receiving roller, cannot be again unrolled except by the use of a key. It will be seen that this is very convenient when messages are to be left which it is not desired to have 40 read by unauthorized persons.

The device further has means for supporting carbon paper above the roll, so that a copy of what is written may be kept.

I have shown in the accompanying drawings 45 an embodiment of my invention, and therein: Figure 1 is a perspective view of my improved copygraph; Fig. 2 is a longitudinal section thereof; Fig. 3 is an under-side plan view; and, Fig. 4 is a fragmentary 50 under-side plan view partly broken away.

Corresponding and like parts are referred to in the following description and indicated

in all the views of the drawings by the same reference characters.

My device takes preferably the form of a 55 rectangular casing having downwardly turned sides and a table. This table, in the drawings, is designated 2, and the downwardly extending side-pieces are designated 3. Mounted at the forward and rear ends 60 of the sides 3 in downwardly and inwardly inclined slots 3^a, are the rollers 4 and 5, 4 designating the delivery roller, and 5 the receiving roller. It will be seen that the receiving roller and the delivery roller are 65 mounted almost immediately below the forward and rear end of the table. Preferably, the table is covered with material giving a smooth writing surface, as for instance, a sheet of smooth metal 6. 70

7 designates a strip of writing or memorandum paper which is primarily wound upon the delivery roll 4 and which extends over the table 2 and passes down at the rear end of the same, over the curved upper edge 75 8 of the table 2, under the curved edge of a cross bar 9, and so to the roll 5. At its forward end, the paper passes over the curved lower edge 10 of the table 2, and between this end 10 and a cross bar 11 which is 80 formed with a rounded face so as not to impede the movement of the paper. In order to guide the paper and hold it in position while permitting the easy movement thereof, I provide the cross bars 12 and 13 which are 85 spaced from the face of the plate 6 and are preferably of metal. These are sufficiently near to the surface of the plate 6 so as to hold the paper in a smooth relation, while permitting its easy movement over the 90 plate 6.

In order to prevent the rolls 4 and 5 from unwinding accidentally, and in order to thereby keep the paper under proper tension, I provide the bowed spring plate 14 which is 95 attached at its middle to a cross-piece 15 and has the upwardly and outwardly curved ends 16 which pass beneath the paper on the rolls 4 and 5 and then extend upwardly and outwardly. The resiliency of this spring 100 plate keeps the ends thereof pressed against the rolls of paper, and the rolls are prevented from any accidental turning movement either forward or backward. This is

of great importance in a device of this kind, as it prevents any rumpling of the paper, and keeps it under proper tension, and prevents accidental turning thereof. The rolls 5 4 and 5 are each provided with the arbors 17 and 18 which extend outwardly through the sides 3 and are provided on their ends with the knobs 19, or other turning means. By 10 means of these knobs, the paper may be rolled from one roll to the other, in either direction. Mounted upon the cross-piece 9, is the clamp 20 having a spring 21, whereby the edge of the clamp is forced downward into engagement with the cross bar 13. This 15 clamp provides for the adjustment, over the paper 7, of a sheet of carbon paper 7^a over which a duplicate record sheet 7^b may be laid.

It will be seen that the carbon paper and 20 duplicate record sheet so supported will not be in close contact with the paper 7, but that the roll of paper may be wound up without affecting the condition of the duplicate record sheet and carbon sheet held by the clamp 25 20. This construction is particularly useful where memoranda of bills are to be made on the sheet 7. The original bills are laid upon the carbon sheet, made out, and then the sheet 7 is wound up so as to provide a new 30 surface for a new bill. While this particular form of my device is particularly applicable to keeping a record of bills, it is to be understood that it may be used for other purposes, as for keeping duplicate records 35 of messages, receipts, prescriptions, etc.

While so much of my invention as I have described furnishes a very convenient means for supporting a continuous sheet of paper and winding it up as it is used, I have provided also a means whereby the sheet when 40 it is once wound up with its message or other memorandum thereon, cannot be unwound unauthorized. To that end, I provide on the arbor 18 and inside of the side-piece 3, a ratchet wheel 22, and engaging therewith and supported pivotally upon the side-piece, is a pawl 23 whose detent tooth engages with the ratchet teeth of the wheel 22, the pawl being forced into engagement by its spring 50 24. The rear end of this pawl is extended beyond the pivot 25, and is adapted to be engaged by an arm 26 which is mounted upon a key spindle 27. Preferably, this arm 26 is rectangular in plan, and has a flat lower 55 face and a flat side face, the flat lower face engaging with the prolongation of the pawl 23, in one position, but being disengaged therefrom when it is turned into the position shown in Fig. 2. The arm 26 and the key 60 arbor 27 thereof are adapted only to be turned by a key fitting the key arbor or an opening made in the arm 26. Under normal circumstances, the spring 28 will hold the arm 26 in its raised position, and thus the

spring 24 will force the pawl into engagement with the ratchet. Hence, the pawl will prevent any unwinding of the paper after it has been wound upon the roller 5. When it is desired, however, to read what has been written upon the paper 5, the person who 65 70 has the key fitting the arbor and arm 26, inserts the same and turns the key so that it engages with the rear end of the pawl, and forces it out of engagement with the ratchet. Upon this disengagement, the roller 4 may 75 be reversely turned, and the paper held upon the roller 5 will be unwound, permitting the messages to be read.

It will be plain that this device is particularly useful where messages are left which 80 it is not desired that unauthorized persons shall read, as for instance, business messages, or messages left for a doctor by a patient.

While I have shown a very simple form of 85 key arbor 27, it is to be understood that I do not limit myself to this, as it is obvious that the key arbor and arm 26 might be so constructed as to require a very peculiarly shaped key to be used in order to unlock the 90 pawl from its engagement.

In the construction heretofore described, I have stated that the rolls are provided with knurled knobs, whereby they may be turned. In many instances, however, as for 95 instance, where my device is of small compass, and is intended to be carried in the hand, it is most convenient that means be provided for automatically winding up the roller 5, and for permitting or controlling 100 this winding movement when desired. To this end, as shown in Fig. 4, I have provided the roller 5 with a winding spring 30 which, in the embodiment shown, is attached to one end of the casing and at its other 105 end to the arbor 18. The pawl and ratchet 22 and 23, previously described, will of course permit of winding up of this spring, the pawl holding the spring from unwinding. At the other end of the roller, I provide a ratchet 31 of any desired character, but shown as a ratchet whose teeth project 110 outwardly or in the direction of the axis of the roller. In connection with the ratchet 31, I provide a pawl 32 pivoted at its middle 115 to the casing, as at 33, and having a spring 34 which depresses it inward into engagement with the ratchet 31. The other end of the pawl 32 is formed with the outwardly extending portion 35 having a button arranged convenient to the hand of the 120 operator. It will be obvious, now, that upon a pressure upon the button, the pawl will be lifted from engagement with the ratchet 31, and that the spring 30 will immediately act to rotate the roller and to wind up the strip of paper thereon. In use, 125 when it is desired to reel up the strip of

paper, it is only necessary to press the button 36, whereupon the pawl will be lifted and the roller will be actuated. Thus, a device of this kind may be used for holding 5 a lecturer's or speaker's notes, and in place of having to manually wind up the receiving roller, it is only necessary to press the button 36. When the paper has been wound off the roll 4 to the degree desired in order 10 to present the proper notes, the pressure on the button 36 is released, whereupon the ratchet 31 is again engaged.

The advantages of my invention are obvious, and by reason of its construction, it is 15 applicable in a large variety of circumstances, and to many uses. While I have shown the forms which I deem preferable, I do not wish to be limited to these, as it is obvious that the details of construction may 20 be changed in many ways, without departing from the spirit of the invention, and that it may be modified to suit it to various uses.

Having thus described the invention, what 25 is claimed as new is:—

1. In a device of the character described, a table, side pieces supporting the table and extending downwardly, a delivery roll mounted in one end of the table a receiving 30 roll mounted at the other end, a web of paper mounted on one of the rolls extending across the face of the table and engaged with either of said rolls whereby the web may be moved across the face of the table, 35 means on the rolls whereby they may be rotated to wind or unwind the paper from one to the other roll, a ratchet wheel carried by the receiving roll, a pawl mounted intermediately of one of the side pieces and 40 engaging with said ratchet wheel, said pawl being extended rearwardly of its pivot, an arm pivotally mounted within the side pieces and adapted when moved to contact with the rear end of the pawl and raise the 45 latter from engagement with the ratchet to release the roll, an arbor on the arm adapted to be engaged by a key to turn into or out of engagement with the pawl, the end of said arm being flat, and a spring engaging 50 with said flattened end or with the side of the arm to hold the arm out of engagement with the pawl or in engagement therewith.

2. In a device of the character described, a table, a delivery roll and a receiving roll 55 mounted at opposite ends of the table, a spring for rotating the receiving roll to wind thereon a web of paper from the delivery roll, a ratchet and pawl for preventing the unwinding of the receiving roll, 60 means for disengaging the pawl from the ratchet to permit said unwinding, said means including a key arbor, a ratchet on the other end of said receiving roll, and a pawl engaging with the ratchet to prevent

the spring from winding up the receiving 65 roll, said pawl having a button projecting through the side of the device whereby the pawl may be operated to disengage it from said ratchet.

3. In a device of the character described, 70 a table having opposed downwardly extending sides, the extremities of said side being provided with open-ended diagonal slots extending downwardly and toward the middle of the sides and inclined to the said table, 75 end cross bars mounted on said side pieces at opposite ends of the table, a delivery roll and a receiving roll mounted beneath said end cross pieces and both being provided with projecting arbors adapted to be received 80 within said slots in the side pieces, cross bars located inward of said end cross pieces spaced from the table and extending across from one side face to the other, a web of paper wound upon the delivery roll ex- 85 tending up over the lower edge of the table, over the face of the table beneath said spaced cross bars, then downwardly beyond the table and around the receiving roll, a spring clamp supported on one of the end 90 cross pieces and having its edge engaging against the outer face of the next adjacent cross bar to hold a piece of transfer paper and a duplicate transfer sheet engaged with 95 said cross bar, means for rotating the receiving roll to wind the web of paper thereon, and a locking device preventing the unwinding of the web of paper from the receiving roll, said locking device including a key arbor.

4. In a device of the character described 100 a table, having opposed downwardly extending side pieces, the extremities of said side pieces being diagonally slotted, end cross pieces mounted on said side pieces at opposite ends of the table, a delivery roll and a receiving roll both provided with projecting arbors adapted to be received within 105 said slotted portions of said side pieces, cross bars spaced from the table and extending 110 across from one side to the other, said cross bars being located inward of the end cross pieces, a web of paper mounted upon the delivery roll and extending across said table and beneath said cross bars, then downwardly over the upper end of the table, to the receiving roll, a spring clamp supported on one end cross piece and having its edge 115 engaging against the upper face of the next adjacent cross bar, a spring connected with the arbor of the receiving roll to rotate the latter to wind the web of paper thereon, opposed ratchet wheels on the arbor of the receiving roll, a pawl engaging with one of the ratchet wheels to prevent the reverse 120 movement of the roll, and lock it against said reverse movement, said pawl being mounted upon the inside face of one of the

side pieces, an arbor projecting through said side pieces and having an arm adapted to engage with the pawl to elevate the same from engagement with the ratchet and hold it disengaged, said arbor being so formed as to be engaged by a key, a ratchet mounted on the opposite side piece, a pawl engaged therewith, and preventing the winding up of the receiving roll, said pawl being provided with a finger button projecting out

through the side piece and adapted to be pressed to raise the pawl out of engagement with the ratchet to permit the spring to rotate the receiving roll.

In testimony whereof I affix my signature 15 in presence of two witnesses.
